LIQUID DISPENSER

Gordon Wettstein, Milwaukee, Wis., assignor of fifty per cent to Salvadore J. Verona, Milwaukee, Wis.

Application May 9, 1955, Serial No. 35,891

Term of patent 14 years

(Cl. D58—10)

Fig. 3

Fig. 1

The dominant feature of my design resides in that portion shown in full lines in the drawing.

I claim:

The ornamental design for a liquid dispenser, as shown and described.
